CLAIM

The ornamental design for the compact carpet extractor, as shown and described.

DESCRIPTION

FIG. 1 is a perspective view of a compact carpet extractor showing my new design;

FIG. 2 is a side elevational view thereof;

FIG. 3 is a front elevational view thereof;

FIG. 4 is a rear elevational view thereof; and,

FIG. 5 is a top plan view thereof.

The second side is a mirror image of FIG. 2.

The undisclosed bottom view is plain and unornamented. The nozzle and hose shown in broken lines in FIG. 1 are shown for illustrative purposes only and form no part of the claimed design.

FIG. 1

FIG. 2

FIG. 3

FIG. 4

FIG. 5
